WHEEL FLANGE LUBRICATOR

Bengt E. Folke, Mamaroneck, and Howard Winther, Harrington Park, N. Y., assignors to Nathan Manufacturing Company, New York, N. Y., a corporation of New York

Application January 29, 1944, Serial No. 520,286

12 Claims.

(Cl. 184—3)

This invention relates to devices for supplying lubricant to the wheel flanges of railway locomotives and cars in order to reduce the friction and wear between the flange of the wheel and the rail.

One of the principal difficulties with existing flange lubricators is that they easily get out of adjustment and thus do not deposit the lubricant at the base of the flange as intended; in fact the oil is frequently deposited on the tread of the wheel instead of at the flange. This, of course, is a serious defect since the locomotive depends on the friction between the wheel and the rail for adhesion, and oil deposited on the tread causes slippage of the wheel and loss of traction power. A flange oiler that deposits the oil in the wrong place on the wheel serves no useful purpose and is, instead, detrimental to the satisfactory operation of the locomotive.

Another difficulty now experienced with flange oilers is that they are hard to adjust properly and for this reason require skillful attention. The flange oiler, being an inconspicuous device, does often receive no attention at all with the result that it does not function as intended.

Certain types of flange oilers are arranged in the form of a shoe or saddle which is held in position by the contour of the wheel flange. This arrangement has the shortcoming, on account of its comparatively heavy weight and high inertia, that, particularly at high speeds, the device does not follow the movement of the wheel smoothly, but instead is thrown up and down, contacting the flange only occasionally with the result that the application of lubricant is not as uniform as desired. It also causes rapid wear of the flange oiler shoe when so operated.

Still another difficulty with some types of flange oilers is that they have loose connections to permit them to follow the movement of the wheel in relation to the structure of the vehicle; no proper provision being made for lubricating these loose connections, they soon wear out, and the device becomes ineffective.

It is the principal object of the invention to provide especially compact means for supplying the lubricant to the wheel flange.

Another object is to provide a flange oiler that will readily adjust itself to the combined up and down and lateral movement of the flanged wheel, in relation to its support, in order to deposit the lubricant at the base of the flange and to prevent oil from being applied to the tread of the wheel.

Further objects are to provide a flange oiler that has the oil inlet arranged stationarily in relation to the supporting bracket, that can easily

be applied, is self-adjusting and self-lubricating, and which embodies means to overcome the before mentioned difficulties experienced with flange lubricators as made heretofore.

5 In the drawings in which a preferred embodiment of the invention is illustrated

Fig. 1 shows a front elevational view of the flange oiler partly in section;

Fig. 2 is a side elevational view;

10 Fig. 3 is a plan view of the flange oiler mechanism;

Fig. 4 is a front elevational view showing the flange oiler at the limit of one of its movements;

Fig. 5 is a side elevational view at the limit of 15 another of its movements;

Fig. 6 is a horizontal sectional view along the plane of line 6—6 in Fig. 4; and

Fig. 7 is a view of the assembled fulcrum member forming part of the device.

20 Like numbers and references denote similar parts throughout the several views and the following specification.

Referring to Fig. 1, 10 is a conduit from a suitable source of oil supply under pressure (not shown). 11 is a fitting containing a check valve 12, held against its seat by a light spring 13 for the purpose of preventing unintentional drainage of the oil from the conduit 10.

Oil is admitted into a threaded opening 14 of 30 a flange oiler bracket 15. The oil is conducted through a port 16 into a drilled passage 17 of a fulcrum post 18, see Figs. 1 and 6. The port 16 is arranged so that it will always be in communication with the passage 17. The fulcrum post 18 is provided with a retaining nut 17 and is arranged to turn around its axis 18.

Referring to Fig. 6, the passage 17 communicates with a passage 19 which connects with a port 20 in a fulcrum pin 21. The fulcrum pin 21 is securely fastened in the fulcrum post 18 by means of a tapered fit, indicated at 22, and a lock nut 23. An oil passage 24 communicates with the port 20 and carries the oil into ports 25 of the fulcrum pin 21.

45 Referring to Fig. 1, the ports 25 are connected by means of an annular groove 26 to a passage 27 in an oil tube support 28, when the oil is carried through the bore 29 of an oil tube 30 to a flange 31 of a flanged wheel 32. 29a is a rod 50 loosely inserted into tube 30 to prevent too copious a discharge of oil.

Referring to Fig. 2, the tread diameter of the wheel is indicated at 32 and the outer flange diameter is indicated at 33.

The oil tube support 28 is free to turn around the fulcrum pin 21.

Referring to Figs. 2, 4 and 5, oil tube support 28 is provided with a lug 34, which limits the angular movement of support 28 by contact against a side 35 of fulcrum post 18. Flange oiler bracket 15 is also provided with a lug 36 which limits the movement of the fulcrum post 18 by contact against a side 37 of fulcrum post 18. By referring to Fig. 2, it will be noted that a lug 38 is located at the top of the flange oiler bracket 15 and that this lug 38 is symmetrical with lug 36 in order to permit the flange oiler bracket 15 to be reversed permitting application on either one side or the other of the vehicle structure. A lug 39 is likewise provided on the opposite side from lug 34 on oil tube support 28 to permit reversing the assembly of the flange oiler.

Referring to Fig. 6, oil seals are provided at 40 and 41 to prevent oil from leaking out around the journal of the fulcrum post 18. Oil seals are also provided at 42 and 43 to prevent oil leakage around the journal bearing of the fulcrum pin 21.

The flange oiler bracket 15 is provided with an extension 44 projecting away from the bracket in a plane substantially at right angles to that of the fulcrum post 18 through the bracket and is provided with a guide pin 44a. 46 is an extension projecting away from the oil tube support 28 in a plane substantially parallel to that of fulcrum post 18 and is also provided with a guide pin 46a. Extensions 44 and 46 are in spaced relation to each other and confine a coil spring 45 between them guided by pins 44a and 46a. The flange oiler bracket 15 is arranged with a suitable extension 49 which may be bolted on a member of the vehicle structure indicated at 50.

The limitation of movement of both the fulcrum member made up of post 18 and pin 21 and the tube support 28 by their respective lugs abutting sides of the fulcrum member is particularly provided for to prevent the spring 45 forcing extensions 44 and 46 apart sufficiently to let the spring 45 become disengaged therefrom. The lugs are so arranged that they will not influence the travel of the oil tube due to the motion of the wheel relative to the main bracket 49 or the vehicle structure, the possible travel of the oil tube being within the limitations caused by the lugs. Their principal purpose is to enable the oiler to be handled and applied as an assembled unit.

In operation, oil is conducted from the oil conduit 10 through the passages as described above and the oil is deposited at the base of the wheel flange 31. The spring 45 by exerting pressure on the extension arm 46 of the oil tube support 28 serves to exert a downward pressure on the oil tube 30 against the wheel 32. The pressure exerted by spring 45 against the extension arm 46 also tends to turn the fulcrum post 18 around its axis 48. The resultant action of the spring 45 causes the oil tube 30 to be pressed downwardly and inwardly and thus to maintain its position at the base of the wheel flange 31, as the wheel moves in and out, and up and down, due to irregularities in the track and the movement of the vehicle structure on its springs.

It will be noted that the individual moving members of the assembly, namely, the fulcrum post 18 within the bracket, and the tube support 28 over the fulcrum pin 21, are well lubricated by the oil passing through the assembly from its inlet 14 to its outlet tube 30. Loss of oil is prevented by the use of the oil seals, as explained. Thus an oiler is presented which is simple to apply, easy to oper-

ate, reliable in performance, and economical to manufacture. The reduction of number of parts to a minimum also reduces its size to an especially compact one.

5 It is understood that various changes in form, proportions and minor details of construction may be resorted to without departing from the principles or sacrificing any of the advantages of the invention as defined in the appended claims.

10 What we claim as new, is:

15 1. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange.

20 2. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange.

25 30 3. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange.

35 35 4. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

40 40 5. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

45 45 6. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

50 50 7. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

55 55 8. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

60 60 9. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

65 65 10. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

70 70 11. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

75 75 12. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means limiting the rotating movement of said member and said support.

said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, and means in said support limiting the rotating movement of said support upon said fulcrum member.

5. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, means in said bracket limiting the rotating movement of said fulcrum member in said bracket, and means in said support limiting the rotating movement of said support upon said fulcrum member.

6. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to said fulcrum member in said bracket, and a spring confined between said extensions, the lengths of said extensions determining the force exerted by said spring to keep said oil tube in continual contact with said wheel flange, means in said bracket limiting the rotating movement of said fulcrum member in said bracket, and means in said support limiting the rotating movement of said support upon said fulcrum member, the travel of said oil tube being less than that controlled by the limits of said rotating movements.

7. A wheel flange lubricator including a main bracket fixedly supported adjacent to the wheel, a fulcrum member rotatably mounted in said bracket, an oil discharge tube adapted to contact the wheel flange, a support for said tube rotatably mounted upon said fulcrum member at substantially right angles to the axis of rotation of said member in said bracket, said bracket having an oil inlet in constant communication, through ports in said fulcrum member and support, with said oil tube, an extension from said bracket substantially parallel to said support and an extension from said support substantially parallel to

said fulcrum member in said bracket, and a spring confined between said extensions, the lengths of said extensions determining the force exerted by said spring to keep said oil tube in continual contact with said wheel flange, lugs symmetrically disposed at both sides of said bracket limiting the rotating movement of said fulcrum member in said bracket, and lugs symmetrically disposed at both sides of said support limiting the rotating movement of said support upon said fulcrum member, said resilient means being disposed symmetrically between the lugs at said bracket and support, respectively.

8. A wheel flange lubricator including a main bracket, fixedly supported adjacent to the wheel, an oil discharge tube adapted to contact the wheel flange, a support for said tube, a fulcrum member, a post extending from one side of said fulcrum member rotatably and oil tightly mounted in said bracket, a pin extending from another side of said fulcrum member and at substantially right angles to said post, the said support being rotatably and oil tightly mounted upon said pin, said bracket having an oil inlet in constant communication, through ports in said fulcrum member, post, pin, and support, with said oil tube, an extension from said bracket substantially parallel to said support and an extension from said support substantially parallel to the post of said fulcrum member in said bracket, and a spring confined between said extensions, the lengths of said extensions determining the force exerted by said spring to keep said oil tube in continual contact with said wheel flange.

9. A wheel flange lubricator including a main bracket, fixedly supported adjacent to the wheel, an oil discharge tube adapted to contact the wheel flange, a support for said tube, a fulcrum member, a post extending from one side of said fulcrum member rotatably mounted in said bracket, a pin extending from another side of said fulcrum member and at substantially right angles to said post, the said support being rotatably mounted upon said pin, said bracket having an oil inlet in constant communication, through ports in said fulcrum member, post, pin, and support, with said oil tube, an extension from said bracket substantially parallel to said support and an extension from said support substantially parallel to the post of said fulcrum member in said bracket, and a spring confined between said extensions, the lengths of said extensions determining the force exerted by said spring to keep said oil tube in continual contact with said wheel flange, means in said bracket for limiting the rotating movement of said post, and means in said support for limiting the rotating movement of said support.

10. A wheel flange lubricator including a main bracket, fixedly supported adjacent to the wheel, an oil discharge tube adapted to contact the wheel flange, a support for said tube, a fulcrum member, a post extending from one side of said fulcrum member rotatably mounted in said bracket, a pin extending from another side of said fulcrum member and at substantially right angles to said post, the said support being rotatably mounted upon said pin, said bracket having an oil inlet in constant communication, through ports in said fulcrum member, post, pin, and support, with said oil tube, an extension from said bracket substantially parallel to said support and an extension from said support substantially parallel to the post of said fulcrum member in said bracket, and a spring confined between said ex-

tensions, the lengths of said extensions determining the force exerted by said spring to keep said oil tube in continual contact with said wheel flange, means in said bracket for limiting the rotating movement of said post, and means in said support for limiting the rotating movement of said support, the travel of said oil tube being less than that controlled by the limits of said rotating movements.

11. A wheel flange lubricator including a main bracket, fixedly supported adjacent to the wheel, an oil discharge tube adapted to contact the wheel flange, a support for said tube, a fulcrum member, a post extending from one side of said fulcrum member rotatably mounted in said bracket, a pin extending from another side of said fulcrum member and at substantially right angles to said post, the said support being rotatably mounted upon said pin, said bracket having an oil inlet in constant communication, through ports in said fulcrum member, post, pin, and support, with said oil tube, lugs symmetrically disposed at both sides of said bracket for limiting the rotating movement of said post, an extension from said bracket symmetrical with and between said lugs, other lugs symmetrically disposed at both sides of said support for limiting the rotating movement of said support upon said pin, an extension from said support symmetrical with and between said other lugs, and resilient means

disposed between said extensions, to keep said oil tube in continual contact with said wheel flange.

12. A wheel flange lubricator including a main bracket, fixedly supported adjacent to the wheel, 5 an oil discharge tube adapted to contact the wheel flange, a support for said tube, a fulcrum member, a post extending from one side of said fulcrum member rotatably mounted in said bracket, a pin extending from another side of 10 said fulcrum member and at substantially right angles to said post, the said support being rotatably mounted upon said pin, said bracket having an oil inlet in constant communication, through 15 ports in said fulcrum member, post, pin, and support, with said oil tube, lugs symmetrically disposed at both sides of said bracket limiting the rotating movement of said post by contact with said fulcrum member, an extension from said bracket symmetrical with and between said lugs, 20 other lugs symmetrically disposed at both sides of said support limiting the rotating movement of said support by contact with said fulcrum member, an extension from said support symmetrical with and between said other lugs, and 25 resilient means, disposed between said extensions, to keep said oil tube in continual contact with said wheel flange.
